SKATEBOARD COURSE STRUCTURE

Goodwin Alarik, La Canada, Calif., assignor to Surfers' World, Inc., Laguna Beach, Calif., a corporation of California

Filed Sept. 13, 1965, Ser. No. 86,972

Term of patent 7 years

(Cl. D34—5)

FIG. 1 is a perspective view of the skateboard course structure showing my new design.

FIG. 2 is a side elevation view of the skateboard course structure disclosed in FIG. 1.

FIG. 3 is a side end elevation view of the skateboard course structure disclosed in FIG. 1.

FIG. 4 is a side view of the skateboard course structure disclosed in FIG. 1.

I claim:

The ornamental design for a skateboard course structure, as shown.
